UNITED STATES PATENT OFFICE.

CHARLES E. HANSEN, OF PROVIDENCE, RHODE ISLAND, ASSIGNOR TO HANSEN-BENNETT COMPANY, A CORPORATION OF RHODE ISLAND.

MATCH-BOX.

No. 855,454.

Specification of Letters Patent. Patented Aug. 11, 1908.

Application filed August 16, 1907. Serial No. 858,659.

To all whom it may concern:

Be it known that I, CHARLES E. HANSEN, a citizen of the United States, residing at Providence, in the county of Providence and State of Rhode Island, have invented certain new and useful Improvements in Match-Boxes, of which the following is a specification, reference being had thereto to the accompanying drawing.

10 My invention relates to match boxes of a portable type and has for its objects, besides the ends commonly sought in this class of articles, a casing peculiarly adapted for the reception of flexible or paper matches, so-called; means within the casing for suitably positioning the heads to be conveniently grasped; means for enabling the match to be ignited without danger of fracture or bending of the match body; and a cheap and convenient fastening means.

Other objects and advantages will be hereinafter set forth in the specification and made the subject of claims.

To the above ends essentially my invention consists in attaching an independent receptacle in the box or casing; in equipping the receptacle with a bearing arm adapted to contact with the box wall; in extending the ignition opening in the receptacle beyond its face upon one side; and in the novel construction of the fastening means.

In the drawings which form a part of this specification, Figures 1 and 2 are front and side elevations respectively of my novel match box in closed position; Fig. 3, a section of the same on line xx of Fig. 2; Fig. 4, a similar section of the box in open position with a portion of the cover broken away; Fig. 5, a section of the complete box on line yy of Fig. 4. Fig. 6, a face view of the interior of the box body with matches inserted therein, and Fig. 7, a detail view of the catch member.

Like referenced characters indicate like parts throughout the views.

My box comprises a casing consisting of a hollow body, 1, and cover, 2, connected at their rear portions by hinges, 3.

The cover has an internal marginal guide flange, 4, along its free edges, and an internal shoulder, 5, adjacent the flange. The portion of the flange, 4, which is upon the front edge of the cover, is provided midway its length with a semi-circular cavity or notch, 6,

adapted to receive an ear, 8, upon the margin 55 of the cover, 1. Soldered to the inner face of the front wall of the box body are an upper and lower metallic loop, 9 and 10, respectively. A flat spring, 11, is fixed by clamping or otherwise at one end in the loop, 10, and its 60 upper end slides through the loop, 9. The marginal integral ear, 8, of the box is provided with an opening, 12, through which slides a thumb pin, 13, projecting from a plate, 14, provided with projections, 15, having beveled hook shaped heads, 16, upon their extremities. The plate, 14, rests against the spring, 11, which normally presses the head, 16, into engagement with the shoulder, 5, of the cover when the box is 70 closed. The receptacle for the matches is preferably, but not essentially, adapted for the insertion of booked matches. That is, the match stems, 17, are of paper or cardboard and arranged in series within covers, 75 18, to which their lower ends are bound. The lower portion of one of the covers is provided as at 19 with a rough surface adapted to ignite a match.

The match receptacle or holder consists of 80 a flat box, 20, preferably with tapering sides, and having an open top. Its ends at their lower portions are each provided with cavities or openings, 21, to receive the ends of pivot pins, 22, fixed in the lower part of the 85 box body. The receptacle is prevented from excessive forward movement by the proximity of its base, 23, to the lower margin of the box body. Integral with or fixed to the rear wall of the receptacle, 20, is a curved bearing 90 arm, 25, preferably of spring metal which normally presses the upper portion of the holder, 20, out of the plane of the box wall, thereby forcing the upper ends of the matches, when the box is opened, beyond the 95 plane of the box body where they may readily be grasped by the fingers for individual removal from the hook.

The front wall of the holder, 20, is provided with an oblong opening, 26, extending to the 100 very end of the holder on its right, by which arrangement no impediment is offered to the course of the match head when the latter is drawn along the rough surface 19, for ignition. The upper portion of the box and 105 cover are preferably deeper or thicker than their lower portion to better conform to the contour of the matches.

What I claim is,

1. The combination with the body and cover of a match box, of pivotally mounted means in the body for holding the matches and means projecting above the upper end of and removable with said pivoted means for pressing the upper portion of said means out of the plane of the box wall when the cover is opened.
- 10 2. The combination with the body and cover of a match box, of a box pivotally mounted in the body, and a spring bearing arm integral with said pivoted box and extended beyond the wall thereof above its upper edge and engaging the wall of the body near the center to normally press the upper portion of said pivoted box out of the plane of the box wall when the cover is opened.
- 15 3. The combination with the body and cover of a match box, of a movably mounted box within the body, pivotal connections between the box and the body, and a bearing arm integral with the box contacting with the wall of the body beyond the upper end of the box.
- 25 4. The combination with the body and cover of a match box, of a movably mounted box within the body, pivotal connections between the box and the body, and a spring arm integral with the box bearing against the wall of the body beyond the upper end of the box.
- 30 5. The combination with the body and cover of a match box, of a box pivotally mounted in the body and provided upon its front wall with an ignition opening extend-
- 35 ing to the end of the said wall to avoid impediment to the removal of the match, of a spring arm upon the box contacting with said body beyond the upper end of the box.
- 40 6. In a match box the combination with the body, of a cover hinged thereto provided with an internal shoulder and a notched adjacent said shoulder, of a flat spring upon the body and fixed at one of its ends, a plate between the spring and body, a thumb pin upon the plate extending beyond the body, projections upon the plate, and beveled hooks upon the projections adapted to engage the shoulder upon the cover.
- 45 7. As an improved article of manufacture, the improved match box herein described, comprising a body and a cover of substantially like parts, means pivotally connecting the same, means opposite the pivots for holding the same in their closed position, a box having tapered sides and open top pivotally mounted in the lower part of the body, the said box having in its front wall an oblong opening extending to the extreme end of the box, and a curved spring bearing arm integral with the pivoted box and extended beyond the same and bearing against the wall of the body, the upper portion of said box and cover being deeper than the lower portion.
- 50 8. In testimony whereof I have affixed my signature in presence of two witnesses.
- 55 CHARLES E. HANSEN.
